AUTOMATIC CHOKE VALVE

Jesse E. Eshbaugh, Flint, Mich., assignor to General Motors Corporation, Detroit, Mich., a corporation of Delaware

Application November 24, 1934, Serial No. 754,591

8 Claims. (Cl. 261—39)

This invention relates to mechanisms for regulating the ratio of fuel to air in the combustible mixture supplied by the carburetor to the cylinders of an internal combustion engine when its temperature is below that at which it is designed to operate.

The mechanism in which this invention resides effects the desired regulation by controlling the position of the choke valve of the carburetor of the engine in accordance with engine operating conditions. The mechanism is so designed that, if the engine is cranked when its temperature is below a predetermined value, it will, until the engine begins to operate under its own power and for a short time thereafter, be supplied with a "super-rich" combustible mixture, that, thereafter, until the temperature of the engine exceeds a predetermined value, it will be supplied with a combustible mixture whose richness varies inversely with the temperature and speed of the engine and that, if, during the period under consideration, the engine tends to stall or the throttle valve of the carburetor is moved toward its open position, there will be a momentary increase in the richness of the combustible mixture supplied to the engine which will prevent stalling of the engine or insure smooth and rapid acceleration.

For a better understanding of the nature and objects of the present invention, reference is made to the following specification wherein there is described the preferred embodiment of the invention which is illustrated in the accompanying drawings.

In the accompanying drawings:

Figure 1 shows, in elevation, mechanism in which my invention is embodied installed on an internal combustion engine.

Figure 2 is a section through the mechanism taken on the line 2—2 of Figure 5.

Figure 3 is an enlarged view of the valve unit which is incorporated in the mechanism.

Figure 4 is a section taken on the line 4—4 of Figure 2.

Figure 5 is a section taken on the line 5—5 of Figure 4.

Figure 6 is a fragmentary view taken as indicated by the arrows 6—6 of Figure 4.

Figure 7 is a perspective view of two of the elements of the mechanism.

In the drawings, the reference 10 indicates a carburetor which is connected to the cylinders of an internal combustion engine by a manifold 11. In the carburetor 10, there is included a butterfly throttle valve 12 which is mounted on a shaft

13 to which an operating arm 14 is secured and a butterfly choke valve 15 which is mounted off-center on a shaft 16 so that the flow of air into the carburetor will tend to open it.

To the intake manifold 11 adjacent the carburetor 10, there is secured by means of screws 17 a hollow body 18 which is divided into upper and lower compartments by a partition 19. In the upper compartment, there is located a metal bellows 20 to whose open upper end there is secured a flange 22 whose outer edge is seated on the upper end of the body and clamped between it and the outer edge of an inverted cup-shaped cover 23 by screws 24. The lower end of the bellows 20 is closed by a head 21 to which there is secured a rod 44 which projects into the lower compartment of the body 18 through an opening in the partition 19. Expansion of the bellows 20 is limited by the partition 19 and contraction thereof is limited by a rod 25 which depends from the cover 23.

The interior of the bellows 20 communicates with the interior of the intake manifold 11 through a transverse bore 26 in the side wall of the cover 23 and a vertical bore 27 which extends through the upper wall of the intake manifold 11, the wall of the body 18 and into the cover 23. In the lower enlarged end of the portion of the bore 27 which is located in the body 18, there is screwed a plug-like element 28 into whose upper surface there extends a cylindrical recess 29 which is encircled by a cylindrical flange 30. From the lower side of the plug-like element 28 a relatively small bore 32 extends into the recess 29. To the cylindrical flange 30, there is secured a combined valve cage and guide 33 within which there is located a poppet valve 34 which is normally seated on the upper end of the flange by gravity and a light spring 35. Through the center of the valve 34, there extends a bore 36 into which there projects a pin 37 which is of slightly smaller diameter than the bore 36. The pin 37 is loosely connected to the upper end of the combined valve cage and guide 33 so that it may flutter during operation of the engine and dislodge any particles of foreign matter which may find their way into the small opening between it and the bore 36.

To the side of the body 18 which is nearest the exhaust manifold 38 of the engine, there is secured a bearing 39 whose inner end extends into the lower compartment of the body. On ears which are formed on an intermediate portion of the bearing, there is seated a cup-shaped housing 40 whose open end is located adjacent the ex-

haust manifold 38 and into whose interior the outer end of the bearing 39 extends. The cup-shaped housing 40 is secured to the body 18 by the screws 41 which extend through the ears on the bearing 38 and secure the latter to the body.

In the bearing 39, there is journaled a hollow shaft 42 to whose inner end there is secured an arm 43. The outer end of the arm 43 is pivotally connected to the rod 44 which depends from the head of the bellows 20 and from an intermediate portion of the arm there projects a finger 51 which extends parallel to and beyond the inner end of the hollow shaft 42. A shaft 45 extends through and is journaled in the hollow shaft 42 and the wall of the housing 18 opposite that through which the bearing 39 extends. To the end of the shaft 45 which extends through the wall of the body 18 opposite that through which the bearing 39 extends, there is secured an arm 46 whose outer end is pivotally connected to one end of a rod 47. The opposite end of the rod 47 is pivotally connected to the outer end of an arm 48 which is secured to the shaft 18 on which the choke valve 15 is mounted.

To the end of the hollow shaft 42 which is located within the cup-shaped housing 40, there is secured a sector 49 in which there is provided an arcuate slot 50 in which a pin 51 is adjustably secured. To the end of the shaft 45 which is located within the cup-shaped housing 40, there is secured the inner end of a bimetallic coil spring 52 whose outer end engages the pin 51 when its temperature is below a predetermined value.

To the shaft 45, between the inner end of the hollow shaft 42 and the wall of the body 18 opposite that through which the hollow shaft extends, there is secured an element 53. The element 53 is a U-shaped piece of sheet metal through whose arms the shaft 45 extends and through whose base which is made of double thickness by folding the sheet metal upon itself extends the screw 58 which secures the element to the shaft 45. On each of the arms of the element 53, there is formed a finger. The finger 59 overlies the finger 57 on the arm 43 and the finger 58 is adapted to engage the abutment 55 to limit movement of the choke valve 15 toward its closed position and to engage the abutment 56 to limit movement of the choke valve toward its open position.

When an engine on which there is installed the mechanism illustrated in the drawings and hereinbefore described is not operating, the choke valve 15 is, unless the temperature of the engine exceeds a predetermined value, held closed by the bimetallic coil spring 52. If, when its temperature is below this predetermined value, the engine is cranked, the choke valve 15 will remain closed or very nearly closed until the engine begins to operate under its own power and, consequently, during this period, the engine will be supplied with the extremely rich combustible mixture which is conducive to quick and easy starting. As soon as the engine begins to operate under its own power, the flow of air past the choke valve 15 will cause it to open partially and the ratio of fuel to air in the combustible mixture supplied to the engine will be decreased. The extent to which the choke valve opens when the engine begins to operate under its own power is dependent upon the speed of the engine and the resistance offered by the bimetallic coil spring 52 which varies inversely with the temperature of the engine, and the combustible mixture sup-

plied to the engine at this time is, although leaner than it was before the engine began to operate under its own power, very rich.

As soon as the engine begins to operate under its own power, withdrawal of air from the interior of the bellows 20 into the intake manifold 11 and, consequently, collapse of the bellows commences. However, because all of the air withdrawn from the bellows must pass through the small opening between the pin 51 and the bore 36 in the valve 34, an appreciable interval of time, e. g., approximately nine (9) seconds, elapses before the bellows is completely collapsed, i. e., until the head 21 of the bellows engages the lower end of the rod 25. As the bellows is collapsed, the rod 44 is raised and the arm 43 and the hollow shaft 42 are rotated in a clockwise direction when viewed as shown in Figures 1 and 2 and in a counter-clockwise direction when viewed as shown in Figure 6. This rotation of the hollow shaft 42 causes the sector 49 and the pin 51 to rotate in the direction in which they are urged when the choke valve 15 moves toward its open position and, consequently, permits the choke valve to move further toward its open position and effects a reduction in the richness of the combustible mixture supplied to the engine without any change in the temperature of the engine. When the head of the bellows 20 approaches the upper limit of its movement, the rotation of the arm 43 brings the finger 57 into engagement with the finger 59 on the element 53. After the finger 57 engages the finger 59, further upward movement of the head of the bellows is positively transmitted to the choke valve and, consequently, by the time that the bellows is completely collapsed the choke valve will be positively opened sufficiently to insure that the combustible mixture supplied to the engine will not be richer than it should during idle operation of the engine. What is said in the two sentences next preceding this is, of course, based on the assumption that the choke valve 15 has not, before the finger 57 reaches the upper limit of its movement, been opened to such an extent that the finger 59 has been moved beyond the upper limit of the path of the finger 57. Of course, if by the time that the head of the bellows reaches the upper limit of its movement, the choke valve has been opened to this extent, it is not desirable that the described action occur and it will not occur.

Because of its proximity to the exhaust manifold 38, the bimetallic coil spring 52 becomes heated during operation of the engine. Increase in the temperature of the bimetallic coil spring 52 causes the end thereof which engages the pin 51 to exert increasingly less pressure thereon and, consequently, as the temperature of the engine increases the bimetallic coil spring offers less and less resistance to movement of the choke valve 15 toward its open position. Therefore, the increase in the temperature of the engine which results from its operation will cause a gradual decrease in the richness of the combustible mixture supplied to the engine from the time the engine begins to operate under its own power until its temperature reaches a predetermined value when it becomes capable of operating properly upon the combustible mixture with which the carburetor 10 is designed to supply it. When the temperature of the engine reaches this predetermined value, the outer end of the bimetallic coil spring 52 becomes disengaged from the pin 51 and, thereafter, the bimetallic coil spring offers no resistance to the movement of the choke valve 75

toward its open position. Because movement of the outer end of the bimetallic coil spring 52 in response to increases in temperature is not opposed by any externally applied forces, the bimetallic coil spring will not be injured even if it becomes heated to an excessively high temperature.

When the pressure within the intake manifold 11 increases, the valve 34 will move off its seat 12 against the resistance of the spring 35 and gases from the intake manifold will rush thereby into the interior of the bellows 20 and cause it to expand. To prevent these gases carrying into the upper end of the bore 21 any particles of foreign matter which might get into and clog the small opening between the pin 37 and the bore 36 in the valve 34, a disc 31 of fine screen wire is secured in the recess 29 in the plug-like element 28. If the temperature of the engine is below a predetermined value, expansion of the bellows will, of course, through the linkage which connects its head 21 to the choke valve 15, cause the choke valve to move toward its closed position. Consequently, if, when the temperature of the engine 25 is below a predetermined value, the throttle valve 12 is moved toward its open position or the engine tends to stall, there will be a momentary increase in the richness of the combustible mixture supplied to the engine which will insure smooth and 30 rapid acceleration or prevent stalling of the engine.

Obviously, the mechanism illustrated in the drawings and hereinbefore described will not affect the position of the choke valve when the 35 temperature of the engine on which it is installed exceeds a predetermined value.

Since, when the engine stops, the pressure within the intake manifold 11 rises and the bellows 20 consequently expands and, when the temperature of the engine falls, the free end of the bimetallic coil spring 52 moves toward the pin 31, it is apparent that, whenever the engine stops, the parts of the mechanism illustrated in the drawings and hereinbefore described automatically move to the positions in which they should 45 be when the engine is cranked to start it.

It may be noted that there may be associated with the mechanism illustrated in the drawings and hereinbefore described the "fast idle device" 50 or "thermostatic throttle stop" disclosed in the Perrine application, Serial No. 618,225, filed June 20, 1932 and that the bimetallic coil spring of this device may be located in the housing for the bimetallic coil spring 52 instead of in a separate 55 housing.

Of course, although I have shown and described the mechanism to which this invention relates mounted on the intake manifold of an engine with the bimetallic coil spring 52 located in juxtaposition to the exhaust manifold thereof, it will be understood that the mechanism may be mounted elsewhere on the engine and that the bimetallic coil spring may be located in juxtaposition to any other heated part of the engine.

65 I claim:

1. In an internal combustion engine, a carburetor, a valve for regulating the ratio of fuel to air in the combustible mixture supplied to the engine by the carburetor, a support, a pressure actuated element mounted on the support, a shaft journaled in the support and operatively connected to the pressure actuated element, another shaft journaled in the support and operatively connected to the valve, a thermally actuated element operatively interposed between the specified

shafts, means on the support for limiting movement of the pressure actuated element, and means on the support for limiting rotation of the second-specified shaft.

2. In an internal combustion engine, a carburetor, a passage through which combustible mixture is conducted from the carburetor to the engine, a valve for regulating the richness of the combustible mixture supplied to the engine by the carburetor, a chamber with a movable wall whose movement in one direction is consonant with movement of the valve in the direction to decrease and whose movement in the other direction is consonant with movement of the valve in the direction to increase the richness of the combustible mixture, a thermostat through which the movable wall of the chamber is connected to the valve, a duct through which fluid may be admitted to and withdrawn from the chamber to move its movable wall connected to the chamber and the mentioned passage, and means within the duct to restrict the flow of fluid more in the direction to move the movable wall in the first-mentioned direction than in the last-mentioned direction.

3. In an internal combustion engine, a carburetor, a passage through which combustible mixture is conducted from the carburetor to the engine, a valve for regulating the admission of air into the carburetor, an extensible and contractile element whose change in length in one direction is consonant with movement of the valve toward its open position and whose change in length in the other direction is consonant with movement of the valve toward its closed position, a thermostat through which the extensible and contractile element is connected to the valve, a duct through which fluid may be admitted to and withdrawn from the extensible and contractile element to change its length connected to the extensible and contractile element and the mentioned passage, and a valve within the duct to restrict the flow of fluid more in the direction to change the length of the extensible and contractile element in the first-mentioned than in the second-mentioned direction.

4. In an internal combustion engine, a carburetor, a passage which connects the carburetor with a cylinder of the engine, a valve for regulating the admission of air into the carburetor, a bellows whose contraction is consonant with movement of the valve toward its open position and whose extension is consonant with movement of the valve toward its closed position, a duct, through which fluid may be admitted to and withdrawn from the bellows to contract and extend it, connected to the bellows and the mentioned passage, a valve in the duct to restrict the withdrawal of fluid from the bellows more than the admission of fluid to the bellows, and a thermally actuated element, whose movement in response to increases in temperature is consonant with movement of the first-specified valve toward its open position and which may move freely in the direction in which it tends to move when its temperature rises, operatively interposed between the bellows and the first-specified valve.

5. In an internal combustion engine, a carburetor, a choke valve which may be moved toward its open position by the flow of air thereby into the carburetor, a passage which connects the carburetor with the engine, a pressure-responsive element, a passage which communicates with the

pressure-responsive element and the first-mentioned passage, a valve mechanism so designed that decreases in pressure in the first-mentioned passage are sluggishly and increases in pressure in the first-mentioned passage are rapidly transmitted to the pressure-responsive element through the second-mentioned passage, and a thermostat which may move freely in the direction in which it tends to move when its temperature rises connecting the pressure responsive element to the choke valve.

6. In an internal combustion engine, a carburetor, a passage which connects the carburetor with a cylinder of the engine, a valve for regulating the richness of the combustible mixture supplied to the engine by the carburetor, a chamber with a movable wall whose movement in one direction is consonant with movement of the valve in the direction to decrease and whose movement in the other direction is consonant with movement of the valve in the direction to increase the richness of the combustible mixture, a thermally actuated element which may move freely in the direction in which it tends to move when its temperature rises operatively interposed between the movable wall of the chamber and the valve, a duct through which fluid may be admitted to and withdrawn from the chamber to move its movable wall connected to the chamber and the mentioned passage, and means within the duct to restrict the flow of fluid more in the direction to move the movable wall in the first mentioned direction than in the last mentioned direction.

7. In an internal combustion engine, a carburetor, a choke valve in the carburetor, a passage through which combustible mixture is conducted from the carburetor to the engine, a pressure responsive element, a duct which communicates with the pressure responsive element and the passage through which combustible mixture is conducted from the carburetor to the engine, means which renders the response of the pressure responsive element sluggish to a decrease and rapid to an increase in the pressure in the passage through which combustible mixture is conducted from the carburetor to the engine, and a thermostat through which the pressure responsive element is connected to the choke valve. 15

8. In an internal combustion engine, a carburetor, a valve for regulating the richness of the combustible mixture supplied to the engine by the carburetor, a passage through which combustible mixture is conducted from the carburetor to the engine, a pressure responsive element, a duct which communicates with the pressure responsive element and the passage through which combustible mixture is conducted from the carburetor to the engine, means which renders the response of the pressure responsive element sluggish to a decrease and rapid to an increase in the pressure in the passage through which combustible mixture is conducted from the carburetor to the engine, and a thermostat through which the pressure responsive element is connected to the valve. 20 25 30

JESSE E. ESHBAUGH.
